UNITED STATES PATENT OFFICE.

MARQUIS D. L. SWANK AND JASPER T. THORNLEY, OF ANDERSON, IND.

STOP-VALVE.

SPECIFICATION forming part of Letters Patent No. 280,413, dated July 3, 1883.

Application filed October 7, 1882. (No model.)

To all whom it may concern:

Be it known that we, MARQUIS D. L. SWANK and JASPER T. THORNLEY, citizens of the United States, residing at Anderson, in the county of Madison and State of Indiana, have invented certain new and useful Improvements in Stop or Relief Valves; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Our invention relates to an improvement in a stop or relief valve; and the novelty consists in the construction and arrangement of parts, which will be more fully hereinafter set forth, and specifically pointed out in the claim.

20 The object of our invention is to provide a means by which, when the device is located in the center or at any convenient point on a pipe connected with a water-tank or steam-boiler, it may be used both as a stop and re-

25 lief valve, either for the purpose of exhausting steam from the boiler or allowing water to flow from the tank, or vice versa, and it may be placed between the check-valve of a pump and the boiler or other similar apparatus where

30 a stop or relief valve or cock is required to open and close pipes from opposite directions, but from only one direction at the same time.

The invention consists, essentially, in a casting, of proper metal, having vertical and horizontal passages which cross each other at right angles, and representing the junction of vertical and horizontal pipes, in which is placed the stop or relief plug or key. The top of the case containing said plug is provided with

35 flanges on opposite sides for the purpose of securing a cap by two screws—one on each side—the cap having a collar on its lower surface, which impinges on a corresponding collar of the plug or key, by means of which the

40 plug may be locked in any direction by tightening the screws whereby the cap is secured to the case or main body of the device. The cap having an aperture to receive the plug, and two recesses on either side, opposite each

45 other, of said aperture, is countersunk to

lower and receive the heads of the screws and securely fasten the cap to the case. The tubular passage in the case or body of the device tapers inwardly toward the bottom, where a shoulder is formed to limit the insertion of the 55 plug, and having two holes opposite each other to allow water or steam to enter as an exit from the connecting-pipes when plug or key is properly adjusted. The key is journaled in the cap, and has a shoulder, by means of 60 which it is retained in position in the case, is tubular nearly two-thirds of its length, the outside tapers slightly downward to correspond with its case or casting, and has a recess formed upon one of its sides nearly to the 65 center of its diameter, which connects with its tubular recess.

Referring to the drawings, Figure 1 represents a central vertical section, and Fig. 2 detail perspective views, of our invention. 70

To enable others skilled in the art to make and use the same, reference is made to the accompanying drawings, which form a part of this specification.

A represents the main body or case, with 75 collar a; C, the cap, provided with aperture c, to correspond with journal c' of a plug or key, and having apertures d d' countersunk for heads of screws, and collar e on the lower surface. 80

D represents the entrance or exit from one direction, and E entrance or exit from another or opposite direction, and F outlet for the escape of steam and water, or either.

G represents the plug or key, having recessed 85 opening H to correspond with apertures D and E in the case, to allow, when the recess is turned opposite either of said apertures, the escape of water or steam, as may be desired.

It will be observed that, when the device is 90 placed in position and the plug adjusted with its recessed opening H opposite to the ports or aperture D in the case A, water or steam, as the case may be, passes through and escapes at the outlet F, but effectually stops and closes 95 the port E; and it may be changed to open the port E and close the port D, allowing water or steam to flow through the channel of exit F. This device cannot be used to close both ports D and F at the same time. 100

What I claim as new, and desire to secure by Letters Patent, is—

The relief and stop valve herein described, consisting of a casting having ports D, E, and 5 F, the plug G, having recessed opening H, and the cap C, having collar e, the whole constructed and arranged as and for the purposes set forth.

In testimony whereof we affix our signatures in presence of two witnesses.

MARQUIS D. L. SWANK.
JASPER T. THORNLEY.
